ADJUSTABLE CHAIR

Frederick B. Eiseman, Clayton, Mo.

Application August 10, 1950, Serial No. 11,714

Term of patent 14 years

(Cl. D15—1)

To all whom it may concern:

Be it known that I, Frederick B. Eiseman, a citizen of the United States and a resident of the county of St. Louis, city of Clayton, and State of Missouri, have invented a new, original, and ornamental Design for an Adjustable Chair, of which the following is a specification, reference being had to the accompanying drawing, forming part thereof.

Fig. 1 is a side view of my new design for an adjustable chair,

Fig. 2 is a perspective view of my chair from the left side thereof showing the seat and back in erect position, and,

Fig. 3 is a perspective view of my chair from

the opposite side and showing the seat and back in lounge position.

I claim:

The ornamental design for an adjustable chair, substantially as shown.

FREDERICK B. EISEMAN.
